UNITED STATES PATENT OFFICE.

S JULIEN SUFFERN, OF SLOATSBURG, NEW YORK, ASSIGNOR TO RAMAPO FINISHING CORPORATION, OF SLOATSBURG, NEW YORK, A CORPORATION OF NEW YORK.

PROCESS OF DECORATING FABRIC AND PRODUCT.

No Drawing.

Application filed May 14, 1927. Serial No. 191,550.

This invention relates to a process of decorating fabric and the product thereof, and the principal object is the new method or process or art of decorating fabrics where-
 5 by a new form of decorated fabric is produced having part of the design or decoration dis-
 charge printed and another part of the de-
 sign printed in metallic colors at the same
 time. Heretofore, commercially speaking, it
 10 has not been possible to decorate or ornament
 fabric in one operation with part of the de-
 sign discharge printed on a colored back-
 ground and another part of the design printed
 in metallic colors at the same time. The
 15 decorative arts have always demanded multi-
 colored designs on colored grounds illumi-
 nated with gold or silver and heretofore such
 styles have been produced by weaving.
 While discharge printing has been used for a
 20 long period of time in decorating fabrics,
 printing part of the design in metal colors on
 the same goods has not been practiced be-
 cause the disadvantages in commercial pro-
 duction have been so great that this combina-
 25 tion has not been practicable. The question
 of alignment, uniformity and arrangement
 of designs and complication of machinery,
 and necessity of using additional machines
 are all factors which have cooperated to the
 30 discouragement of practice of this character.
 It would have required two operations with
 the attendant troubles, difficulties and dis-
 advantages and inability to produce a design
 or ornamentation uniform and properly
 35 placed, so as to be commercial.
 In my new process the discharge printing
 and the printing with metallic colors are car-
 ried on at one and the same time and in one
 apparatus with the resultant advantages of
 40 economy in operation, complete and accurate
 registration and alignment and positioning
 of designs and uniformity of appearance of
 the resulting product. The process is prac-
 ticed on the standard form of machine and
 45 involves the discharge printing of a part of
 the design, decoration or ornamentation on
 the fabric simultaneously with the printing
 in metal colors of another part of the design
 on the same goods.

This process may be used for treating 50
 fabrics or cloths of cotton, silk, mixed or
 artificial materials. These multi-colored dis-
 charges can be made from basic, chrome, pig-
 ment and vat colors.

In discharge printing the fabric is dyed 55
 in the form of a suitably colored background.
 In printing the discharge color the colored
 background is simultaneously discharged and
 the design is printed on the fabric. In this
 new process in addition to these operations, 60
 the metal color ornamentation or decoration
 is applied at one and the same time to the
 same fabric. It is understood that in re-
 ferring to metal colors I refer to gold, silver,
 65 copper, bronze and the like.

The practice of this process results in a
 very effective and inexpensive method of
 producing a multi-colored discharge printed
 fabric with a metallic colored design in com-
 bination therewith. This is a very unique 70
 and remarkable product in this art.

What I claim is:—

1. The process of decorating fabrics which
 includes the printing of discharge colors on
 the fabric simultaneously with the printing 75
 of metallic colors on the fabric.

2. The process of decorating fabrics which
 includes the printing of discharge colors on a
 colored background simultaneously with the
 printing of metallic colors thereon so as to 80
 form a combination discharge printed and
 metallic colored design or ornamentation on
 the fabric.

3. In the art of decorating fabrics, the step
 which includes the simultaneous printing of 85
 the design or ornamentation by discharge
 colors and also metallic colors.

4. In the art of decorating fabrics, the step
 which includes the printing of part of the
 design or ornamentation by discharge colors 90
 simultaneously with the printing of another
 part of the design or ornamentation in metal
 colors.

In testimony that I claim the foregoing, I
 have hereunto set my hand this 10th day of 95
 May, 1927.

S JULIEN SUFFERN.
